US0D1104416S

(12) **United States Design Patent** (10) **Patent No.:** **US D1,104,416 S**
(45) **Date of Patent:** **** Dec. 9, 2025**

(54) **APPAREL**

(71) Applicant: **Abigail Marie Britt**, Nunica, MI (US)

(72) Inventor: **Abigail Marie Britt**, Nunica, MI (US)

(**) Term: **15 Years**

(21) Appl. No.: **29/893,725**

(22) Filed: **Jun. 1, 2023**

(51) LOC (15) Cl. **02-02**

(52) U.S. Cl.

USPC **D2/840**; D2/853

(58) **Field of Classification Search**

USPC D2/840, 700, 703, 705, 717, 728, 731,
D2/734, 750, 841, 853

CPC ... A41D 13/0015; A41D 1/04; A41B 2400/38

(57) **CLAIM**

The ornamental design for apparel, as shown and described.

DESCRIPTION

FIG. 1 is a front perspective view of apparel, showing my new design.

FIG. 2 is a left side view of the apparel of FIG. 1. The right side view is a mirror image of the left side view.

FIG. 3 is a front view of the apparel of FIG. 1.

FIG. 4 is a rear view of the apparel of FIG. 1.

FIG. 5 is a top view of the apparel of FIG. 1.

FIG. 6 is a bottom view of the apparel of FIG. 1.

FIG. 7 is a cross-sectional view of the apparel taken along line VII of FIG. 2; and,

FIG. 8 is a cross-sectional view of the apparel taken along line VIII of FIG. 2.

The short-short broken lines shown in figures depict stitching that form part of the claimed design.

1 Claim, 7 Drawing Sheets
